UNITED STATES PATENT OFFICE.

EDWIN S. PRIDHAM AND PETER L. JENSEN, OF OAKLAND, CALIFORNIA, ASSIGNEES
TO MAGNAVOX COMPANY, OF OAKLAND, CALIFORNIA, A CORPORATION OF ARIZONA.

ELECTRODYNAMIC RECEIVER.

Application filed April 28, 1920. Serial No. 377,354.

To all whom it may concern:

Be it known that we, EDWIN S. PRIDHAM and PETER L. JENSEN, citizens of the United States, residing at Oakland, in the county 5 of Alameda and State of California, have invented a new and useful Improvement in Electrodynamic Receivers, of which the following is a specification.

This invention relates to telephones and 10 more specifically to improvements in the moving coil type of telephone receivers. The receiving instrument which is the subject of this specification comprises an annular coil rigidly connected to the diaphragm. 15 This coil is disposed, so as to be freely movable, in a strong concentric magnetic field produced either by a permanent or an electromagnet. The magnetic field is so arranged that the lines of force cut the annular coil at all points in the same direction. 20 This is accomplished by having one of the poles of the magnet within the coil and the other completely surrounding it.

In the accompanying drawings, we have 25 shown two devices of magnetizing structure, namely permanent magnet and an electromagnet.

Fig. 1 shows a plan view of the device 30 using an electromagnet as the magnetizing structure.

Fig. 2 shows a vertical cross-section of the device shown in Fig. 1.

Fig. 3 shows an enlarged detail sectional 35 view of a portion of the device shown in Fig. 2.

Fig. 4 shows a vertical cross-section of the device in modified form using a permanent magnet as the magnetizing structure.

Fig. 5 is a diagram showing the electrical 40 connections for the receiver.

Referring now in detail to the drawings, 2 is the sound box, 3 the diaphragm, 4 an insulator frame with a trough or depression cut into it and forming an annular 45 groove in which the coil 5 is fixed. This insulator frame 4 is rigidly attached to the diaphragm by means of the bracket support 6 and is held in place on the diaphragm by the screw 7 and lock nut 8. The pole 50 piece 9 is provided with a circular hole of sufficiently great diameter to admit the coil 5 with a few thousandths of an inch clearance. Rigidly attached to the pole piece 9

by means of the set screws 10—10 is the spacing ring 11. The inside diameter of this 55 spacing ring is a few thousandths of an inch less than the inside diameter of the insulator frame 4. The pole piece 12 is of substantially the same diameter as the inside diameter of the spacing ring 11. The 60 pole piece is held securely in position in the spacing ring 11 by means of set screws 13—13.

The assembly is then a unit and can be placed on any magnetizing structure de- 65 signed for it.

In Fig. 4, we have shown the assembly adapted to be used with a permanent magnet. In this case, the inner pole piece 12 is fixed to an extension 12^a of one of the poles 70 S. The pole piece 9 is fixed to the pole N of a permanent magnet. The sound box with the diaphragm and coil are fixed in relation to the pole piece 9 and may be removed as a unit from the structure. 75

In Fig. 1 we have shown the receiver head assembly which is the name given to the sound box diaphragm, coil and upper pole piece, adapted to be placed upon an electromagnetic structure. The electromagnetic 80 structure consists of an iron cylinder 14, and iron base 15. The magnetizing coil 16 wound on the core 17 is placed within the iron cylinder to form a substantially closed magnetic circuit when the pole pieces 9 and 12 are in 85 position. The iron core 17 of the magnetizing coil 16 is bored out to form a seat for the pole piece 12 so as to make a good magnetic contact. It will be seen that the receiver head can be assembled as a unit apart 90 from the magnetizing structure and can be placed on or removed from any magnetizing structure adapted to receive it.

We have found that the greater the density of magnetic flux in the airgap, the 95 greater the efficiency of the instrument. Therefore, the instrument must be designed so as to utilize to the highest degree the magnetic flux of the magnetic structure. For this reason it will be apparent that the cross 100 section of the air gap must not be greater than the cross section of the central pole. Thus the depth of the airgap for maximum efficiency cannot be more than one quarter of the diameter of the central pole, as the area 105 of the cylinder equals the cross section of

the cylinder when the altitude of the cylinder is equal to one-fourth its diameter.

Thus, since the moving annular coil must be so designed as to utilize the full flux existing in the airgap, the depth of the coil should be made one fourth its diameter. In the instrument which is the subject of this invention, this construction of airgap and coil is followed with highly successful results.

10 After the correct spacing of the ring in relation to the surrounding pole piece is obtained, the inner pole piece is securely fastened to the spacing ring. Thus we have a unit assembly of sound box with its dia-
15 phragm and coil, outer pole piece and inner pole piece all in correct relation and ready to be mounted on the magnetizing structure.

We have made certain mechanical improvements in the receiver which have aided greatly in the construction of the instrument. As mentioned above, the flux density should be as great as possible so for this reason the width of the airgap should be kept a minimum just sufficient to admit the moving annular coil with a few thousandths of an inch clearance on either side. With such a small clearance it is important that the inner pole be accurately spaced in relation to the surrounding pole. We have also found it to be advantageous to construct the inner and outer pole as a unit with the sound box and movable coil so that they can be placed or removed as a unit on the magnetizing structure. In this way a receiver head or unit as the assembly of inner and outer pole pieces with the sound box and movable coil is termed can be fitted to any magnetizing structure (such as a permanent magnet or electromagnet) for which it has been de-
40 signed.

The inner pole piece is rigidly held in fixed relation to the outer pole piece by means of the spacing ring 11. When this spacing ring has been fixed in proper relation to the outer pole piece, its inner diameter is such that the inner pole piece is held in proper relation to the outer pole piece and the airgap is fixed. The inner pole piece is held rigidly in the spacing ring by means of set screws.

45 The great advantage secured by this mechanism lies in the fact that the sound box, with its diaphragm and coil can be mounted and fixed in position on the pole piece which surrounds the coil, and then by fixing the spacing ring on this surrounding pole piece, the inner core or pole piece is caused to position itself correctly in relation to the movable coil.

60 This receiver has several unique advantages, the movable coil is so designed that its altitude is substantially one quarter the diameter of the inside pole piece 12, thereby taking advantage of the maximum number of lines of force existing in the inner pole

piece at the maximum density. The construction is such as to permit ease of assembling and adjusting and fixing the relation of the pole pieces to the movable coil. It permits of flexibility in manufacturing operations, as the receiver head and the magnetizing structure may be completed independently and then assembled to form the complete unit.

The advantages secured by this construction are very evident. The sound box with its diaphragm and coil can be mounted in fixed relation with the upper pole piece 9. The spacing ring is then adjusted and fixed on the pole piece 9 by means of the set screw 10—10, so that there will be uniform clearance between the pole piece 12 and the frame 4, when this pole piece 12 is put in place in the ring 11. The set screws 13—13 are then tightened to prevent any movement of the pole piece 12.

The electrical connections for the receiver are shown in Fig. 5 and include an operating circuit 18 for the magnetizing coil 16. A transmitter 19 having an operating circuit 20 is also shown. Included in this operating circuit is the primary of an induction coil 21, the secondary of which is connected electrically with the vibrating coil 5.

Having thus described our invention, what we claim and desire to secure by Letters Patent is:

1. In an electro-dynamic receiver, a casing, a magnetizing structure within the casing and a receiver head assembly to fit over the casing, said assembly including a sound box having a diaphragm, a movable coil carried by the diaphragm, an outer pole piece fixed to the sound box, a spacing ring fixed to the outer pole piece and an inner pole piece carried by the spacing ring, said pole pieces being arranged to co-operate with the magnetic structure within the casing.

2. A receiver head assembly comprising an outer pole piece, a sound box including a diaphragm mounted upon and connected to said pole piece, an annular coil fixed to said diaphragm and extending into a central opening in said pole piece, an inner pole piece extending within the annular coil and spaced therefrom, a spacing ring connected to the outer pole piece and supporting the inner pole piece, the foregoing parts forming one unit of an electro-dynamic receiver and a magnetizing structure forming a separate unit with which said pole pieces co-operate.

3. In a telephone of the moving coil type, a sound box including a diaphragm, an annular coil rigidly attached to said diaphragm, a circumferential pole piece surrounding said coil and spaced therefrom, a spacing ring detachably mounted on said circumferential pole piece and supported thereby, and an inner pole piece detachably mounted

in said spacing ring, said inner pole piece extending within the annular coil and spaced therefrom.

4. In a telephone receiver of the moving coil type, a magnetizing structure, a receiver head or operating structure adapted to be placed upon or removed from said magnetizing structure as a unit, said receiver head comprising a circumferential pole piece, a sound box supported upon said circumferential pole piece, a diaphragm on the sound box, a coil on the diaphragm extending into a central opening formed in the circumferential pole piece said coil being surrounded by said circumferential pole piece, a spacing ring mounted upon said pole piece, and an inner pole held in position by said spacing ring and extending within but free from said annular coil, said receiver head and said magnetizing structure adapted to fit together to form a working magnetic circuit for the purposes as set forth.

5. In an electrodynamic telephone receiver, a receiver head comprising as a unit assembly a sound box including a diaphragm, an annular movable coil rigidly fixed to said diaphragm, a pole piece completely surrounding said coil but free from it, a spacing ring mounted upon said pole piece, a second pole piece held in said spacing ring and extending within but free from said annular coil, means for connecting said coil to a telephone circuit, in combination with a magnetizing circuit, said magnetizing circuit comprising a unit assembly as follows, a casing having a base, said casing and base being of magnetic material, an energizing coil having an iron core contained within said casing, said iron core being fastened at one end to the base of the casing, the other end of said iron core being bored out to form a seat for said second pole piece of said receiver head, and connections to said energizing coil for the passing of the magnetizing current.

6. In an electro-dynamic receiver, the combination of inner and outer pole pieces having a circumferential air gap between them, an annular coil arranged in said air gap, said coil including an insulator frame carrying a large number of turns of fine wire a sound box including a flexible diaphragm and means for rigidly connecting said coil and diaphragm, said means including a conical open-sided member connected at its apex to the diaphragm and at its base to the insulator frame.

7. In an electro-dynamic receiver, the combination of inner and outer pole pieces having a circumferential air gap between them, an annular coil arranged in said air gap, said coil including an insulator frame having a depression cut therein and a large number of turns of fine wire arranged in

said depression, a sound box carrying a flexible diaphragm and arms extending up from said insulating frame to the diaphragm for rigidly connecting said annular coil to the diaphragm.

8. An electro-dynamic receiver comprising a shell or casing having bottom and side walls formed of magnetizable material, a magnetizing coil within said casing, a core for the coil extending from the bottom of the casing to the top thereof and formed at its upper end with an inner pole piece, an outer pole piece in the form of a flat plate arranged upon the casing and having a central opening surrounding the inner pole piece and spaced evenly therefrom, means within the casing for retaining said pole pieces in spaced relation, a sound box carried by the casing, said sound box including a diaphragm and a movable coil rigidly connected to the diaphragm and arranged within the space between the two pole pieces.

9. An electro-dynamic receiver comprising a base of insulating material, a shell or casing having bottom and side walls of magnetizable material arranged upon the base, a magnetizing coil within the casing, a core for said coil contacting with the bottom of the casing and extending to the top thereof and formed at its upper end with an inner pole piece, an outer pole piece formed with a flat plate arranged upon the casing and having an opening surrounding the inner pole piece and spaced evenly therefrom, means within the casing for retaining said pole pieces in spaced relation, a sound box carried by the casing, said sound box including a diaphragm and a movable coil rigidly connected to the diaphragm and arranged within the space between the two pole pieces.

10. An electro-dynamic receiver comprising a shell or casing having bottom and side walls formed of magnetizable material, a magnetizing coil within the casing, a core for said coil having contact at its lower end with the bottom of the casing, an extension on the upper end of the core forming an inner pole piece, an outer pole piece in the form of a plate removably mounted on the casing, said outer pole piece having an opening spaced circumferentially from the inner pole piece, means within the casing for retaining the pole pieces in spaced relation, a sound box arranged upon the outer pole piece and supported thereon, said sound box including a diaphragm and an annular coil rigidly connected to the diaphragm and arranged within the space between the two pole pieces.

In testimony whereof we have hereunto set our hands.

EDWIN S. PRIDHAM.
PETER L. JENSEN.
